AIR HEATER

Frederic O. Hess, Philadelphia, Pa., assignor to
The Selas Company, Philadelphia, Pa., a cor-
poration of Pennsylvania

Application March 5, 1938, Serial No. 194,962

8 Claims. (Cl. 263—19)

The general object of the present invention is to provide an improved heater for gaseous fluids, of the type commonly referred to as an "air heater," and devised and adapted for use in heating air or other gaseous fluid up to a temperature of 1500 or 1600° F., for industrial or other purposes.

My improved heater comprises a heating space, through which the fluid to be heated is passed, having refractory walls and including a burner chamber in which the burner element of the heater is mounted, and specially shaped inlet and outlet passages communicating through said chamber. In the preferred construction, for conditions of use which do not prohibit the admixture of the air or other gaseous fluid heated, with the products of combustion of the fuel burned to liberate the heat used in the heating operation, the burner element is a so-called ribbon burner which extends transversely to the direction of flow of the liquid heated and is encased in refractory material and discharges products of combustion into the heating space. The burner is supplied with a combustible mixture of air and fuel gas, and may be, and preferably is, of a type in which the tendency of the flame to "blow off" is reduced to a practical minimum, thereby increasing the safety factor in the use of the improved heater.

My improved air heater is adapted for a wide variety of industrial uses, such, for example, as in heating drawing furnaces, drying chambers, chambers for annealing non-ferrous metals, stress relieving furnaces, low temperature glue heating, and lithographic, polymerizing and other ovens. The form of heater just described has various advantages, some of which are also obtainable with a form of my general invention in which a heating element in the form of a closed heater is located in an intermediate portion of a heating space generally like that of the burner first described. In the last mentioned form of the invention, the burner products of combustion are not admixed with air or gas being heated.

My improved air heater is characterized in particular by its thermal efficiency, its compactness and its relatively low inherent cost of manufacture. The invention is further characterized by the permitted flexibility in its design whereby the size and general form of a unit can readily be made whatever is most convenient for a particular use, and by the further fact that the air heater may be a mechanical unit of such character and form that a plurality of such units may be connected in parallel or in series to provide an effective volumetric or temperature rais-

ing capacity, respectively, which is greater than is conveniently or practically obtainable with a single unit. The heater inlet and outlet are preferably in alignment so the heater may readily be located directly in a straight pipe or conduit line. Operatively, my improved air heater is characterized by the wide capacity range of an individual unit and by the fact the heating space with its inlet and outlet may be so shaped and proportioned, that in moving through the heater, the fluid heated will suffer only a relatively small loss of pressure head, so that the cost of draft fan operation may be correspondingly low. When necessary or desirable for use in circulating and heating furnace atmosphere gases, the heater may well be incorporated in the wall of the heating furnace. My invention in the first described form including an open burner, is characterized by the intimate mixture of products of combustion with the gaseous fluid heated which is effected, and by the fact that when the gaseous fluid heated includes combustible constituents, the latter may be readily burned in the heater, with efficient utilization of the heat liberated.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described preferred embodiments of the invention.

Of the drawings:

Fig. 1 is an elevation of a heater including an open burner, and of the heater connections, with the heater shown in section on the line 1—1 of Fig. 2;

Fig. 2 is a plan section on the line 2—2 of Fig. 1 with the burner element of heater partly broken away and in section;

Fig. 3 is a somewhat diagrammatic elevation of a heating furnace, or oven, having one form of my air heating means incorporated in its wall;

Fig. 4 is a perspective view of a burner assembly part;

Fig. 5 is a section on the line 5—5 of Fig. 6 of an air heater including a closed burner; and

Fig. 6 is a section on the line 6—6 of Fig. 5.

In the drawings, and referring first to the construction shown in Figs. 1 and 2, A represents the refractory material which surrounds and forms the wall of the heating space, or flow passage, of an air or gas heater unit of preferred form. As shown, the said space comprises a burner

chamber C in the form of a horizontal cylinder receiving air or other gas to be heated at its underside through an inlet portion D of the flow passage, and delivering the gas which is heated, 5 admixed with the heating gases, to an uprising outlet portion E of the flow passage. The refractory material A is ordinarily enclosed by a metallic housing B.

Mounted in the chamber C, and spaced away 10 from the peripheral wall thereof, is a burner element F encased in and surrounded by refractory material G which is formed at its upper side with a slot G', through which the burning gases leaving the burner, are delivered axially into the 15 passage E. In the preferred form shown, the burner element comprises a hollow metallic body, or manifold member, formed with a slot F' in its upper side, and comprises a multiplicity of thin plates H of ceramic material, and comprises 20 means for clamping said plates against the metallic burner body, so that each plate extends transversely across the slot F'. The various plates H are shaped to collectively constitute a wall or body of refractory material of flanged bar 25 form, which closes the slot F', except for burner orifices formed by grooves H' in the side faces of the plates H. As shown, each plate H is provided with shoulder extensions H² for engagement by means clamping it to the burner body, 30 and is formed at its edge remote from the burner body with extensions H³, which form the opposite sides of a trough-shaped combustion space, to the bottom of which the channels H' open. The burner element shown herein comprises various 35 features of construction and arrangement, which are novel with me, but are not claimed herein, as they are disclosed and claimed in my application, Ser. No. 320,189, filed Feb. 21, 1940.

The burner body is shown as adapted to receive 40 a combustible mixture of air and gas at one end, through a supply pipe F², and in the case of relatively large burners, a combustible mixture supply pipe may be connected to each end of the burner body. As shown in Fig. 2, the burner element has end portions mounted in aligned portions A' of end walls of the chamber C, which 45 are removable to facilitate the insertion, removal, and replacement of the burner element. As shown, a centering part or shaft-like axial extension, G², is connected to the end of the burner body remote from the pipe F². The heat insulation casing or jacket G for the metallic burner body serves by restricting the transfer of heat between the gaseous fluid being heated and gaseous 50 products of combustion to the burner body, to maintain the metallic burner body at a desirably low temperature.

The type of burner element shown is especially 55 well adapted for its described use, because the ceramic plates H are the only portions of the burner exposed to the heat absorption from the flames, and are well adapted to continuously withstand the temperatures to which they are subjected, and also because a burner of the type shown is adapted for operation with widely different rates of combustion, and in operation with a relatively high rate of combustion, the risk of having its flame blown off is relatively slight. While the type of burner shown is thus especially 65 suitable for use in my improved air heater, those skilled in the art will understand that the air heater may include, and will operate effectively, 70 with burners of other types.

As shown in Figs. 1 and 2, the air or other 75 gaseous fluid to be heated, is moved through the

heater by a fan I driven by an electric motor I', and having its outlet I² connected to the inlet passage D of the heater. The heated air or gas is discharged from the heater outlet E, into a conduit J, shown as jacketed. When the heater 5 is used to heat the gases constituting the atmosphere of a heating chamber or oven, the inlet I³ of the fan may be connected to an outlet port in the wall of the heating chamber or oven, and the pipe J may lead to an inlet port to the oven 10 chamber.

To minimize pressure head loss, and to insure an intimate mixture of the air or gas being heated with the products formed with the combustion of the fuel supplied to the burner element, the 15 flow passage collectively formed by the parts D, C and E are streamlined. Preferably, the portion of the chamber C at opposite sides of the burner element, are shaped so that each forms a nozzle converging, as does the inlet nozzle of a 20 Venturi passage, while the discharge passage F is shaped to form a nozzle expanding as does the discharge nozzle of a Venturi passage.

As previously stated, my improved air heating provisions may be incorporated in the wall of an 25 oven or furnace, and one arrangement of the sort is shown in Fig. 3, where K' represents the heating, or oven, chamber of a furnace or oven K, and K² represents the hearth or bottom wall of the chamber K'. A passage L' in the hearth K² leads from the chamber K to the inlet of a fan IA, which discharges into oppositely directed discharge passages L'. Each discharge passage L' opens into the bottom wall of a burner chamber CA, formed in the corresponding lower corner 30 of the oven or furnace K. Each chamber CA opens into the corresponding chamber E' through an expanding outlet nozzle passage EA. A burner element FA is disposed in each chamber CA. Each element FA may be exactly like the burner 40 element F first described, in general form and in respect to its refractory material casing, and in that it is arranged to discharge burning gases axially into the corresponding discharge passage EA. 45

For use under conditions making it desirable to avoid admixture of products of combustion with the air or gas being heated, I have devised the form of my invention shown in Figs. 5 and 6. The heater shown in Figs. 5 and 6 comprises a 50 heating space or passage formed in refractory material A, which may be similar in shape to the heating space or passage shown in Fig. 1. Actually, however, the single cylindrical burner space C of Figs. 1 and 2 is replaced in Figs. 5 and 6 55 by upper and lower heater spaces CB and CC, each of cylindrical form. As shown, the two chambers CB and CC have the same diameter, and have their axes separated by a distance somewhat less than the diameter of each chamber, so 60 that the two chambers merge into one another and are connected by a communicating port CD which may be of about the same horizontal width as the upper end of the inlet passage D.

The heater element shown in Figs. 5 and 6, is 65 of the enclosed burner type, comprising a tubular metallic body having upper and lower horizontal portions M and MA, each connected at one end to the other through a return bend portion M', and comprising a burner element proper. 70 Said burner element O, extends axially into the burner body M, at its end remote from the return bend M'. The burner element O discharges into the latter burning jets of fuel gas and combustion air in a direction parallel to the axis of the por- 75

tion M. The burning gases or resultant products of combustion flow through the body M, and thence into the body portions MA through a return bend connecting portion M'. As shown, the return bend is embedded in the refractory material A at one side of the heater, and at the opposite side a pipe P supplies a combustible mixture of air and gas to the burner element O, and the products of combustion pass from the burner body portion MA into a waste gas discharge pipe p'. Advantageously, and as shown, the burner body parts M and MA are provided with heat absorbing circumferential ribs or fins M² of thin metal.

16 The tubular parts M and MA may be eccentrically located in the chambers CB and CC, respectively, so as to obtain all of the streamlining and streamlining advantages obtainable with the construction shown in Figs. 1 and 2. With the 20 type of burner shown in Figs. 5 and 6, however, the construction may well be simplified, in some cases, by having the parts M and MA coaxial with the chambers CB and CC, respectively, so that the gas passages curving about the opposite sides 25 of the parts MA and MB, between those parts and the adjacent walls of the chambers CB and CC, respectively, do not change in cross section along their lengths.

While in each of the forms of the invention 30 illustrated, as described, the burner element is shown as horizontally disposed, a burner of either type described, will operate efficiently in any position, so that the burner orifices may be directed upwardly, downwardly, horizontally, or at an angle 35 to the horizontal, as conditions make desirable.

As will be apparent to those skilled in the art, the heater types and forms illustrated and described in detail herein, are well adapted for 40 their intended purposes and objects. The relatively small heater bulk required for a given gas heating capacity, desirable from the standpoint of space economy, and also because it contributes to low construction cost, is made possible in part, by what I have referred to as the streamlining of the flow passage through the heater. That streamlining makes it possible to 45 keep the maximum cross section of the flow passage small, while keeping the resistance to flow and pressure drop in the heater desirably low. The heaters are designed to secure a relatively high velocity of gas flow over the outer surface of the casing G of the burner elements shown in Figs. 1, 2, and 3, and over the parts M and MA 50 shown in Figs. 5 and 6, which contributes to a desirably large rate of heat absorption from the burner element. The relatively high gas velocity in the outlet nozzle portion E, and particularly at the entrance end of the latter, insures that under 55 all practical operating conditions, the flow is sufficiently turbulent to insure rapid equalization of the temperatures of all portions of the fluid flowing through the outlet passage, and such relatively high gas velocity also insures uniform 60 admixture of the products of combustion with the gas being heated.

While in accordance with the provisions of the statutes, I have illustrated and described the best form of embodiment of my invention now 65 known to me, it will be apparent to those skilled in the art that changes may be made in the forms of apparatus disclosed, without departing from the spirit of my invention as set forth in the appended claims, and that in some cases certain 70 features of my invention may be used to advan-

tage without a corresponding use of other features.

Having now described my invention, what I claim as new and desire to secure by Letters Patent, is:

1. A heater for gaseous material, comprising refractory material surrounding and forming a heat insulating wall for a streamlined flow passage including one or more chambers, each extending transversely to the length of said passage, and inlet and outlet portions opening to said chamber or chambers at opposite sides of the latter and each increasing in cross section as the distance from said chamber increases, and an elongated heating element located in and extending longitudinally of each such chamber and spaced from the wall of said chamber to provide passages at the opposite sides of the element through which the gas passing from said inlet portion to said outlet portion, flows in divided streams. 10

2. A heater for gaseous material, comprising a flow passage including a heating chamber extending transversely to the length of said passage, and inlet and outlet portions opening to said burner chamber at opposite sides of the latter, an elongated burner located in and extending longitudinally of said chamber and spaced from the wall of said chamber to provide passages at the opposite sides of the burner element through which the gas to be heated flows in divided streams from said inlet portion to said outlet portion, said burner having an inlet for gaseous fuel and having burner orifices opening to said passage. 20

3. A heater for gaseous material, comprising refractory material surrounding and forming a heating insulating wall for a flow passage, said passage including a burner chamber extending transversely to the length of said passage, and inlet and outlet portions opening to said burner chamber at opposite sides of the latter, a burner located in and extending longitudinally of said chamber and spaced from the wall of said chamber to provide passages at the opposite sides of the burner element through which the gas to be heated flows in divided streams from said inlet portion to said outlet portion, said burner being formed with a fuel space and with burner orifices opening from said space toward the outlet portion of said passage. 30

4. A heater for gaseous material, comprising a flow passage surrounded by a heat insulating wall of refractory material and including an elongated cylindrical burner chamber extending transversely to the length of said passage, and inlet and outlet portions opening to said burner chamber at opposite sides of the latter, a burner located in, and extending longitudinally of said chamber and comprising a hollow metallic body portion and an outer portion of refractory material, spaced from the wall of said chamber to provide passages at the opposite sides of the burner element through which the gas to be heated flows in divided streams from said inlet portion to said outlet portion, said burner having a fuel space within said hollow body and burner orifices opening to said passage. 40

5. A heater for gaseous material, comprising a flow passage including an elongated burner chamber extending transversely to the length of said passage, and inlet and outlet portions opening to said burner chamber at opposite sides of the latter, a ribbon burner adapted for the combustion of a combustible mixture of air and gas, located in and extending longitudinally of said 50

- chamber and spaced from the wall of said chamber to provide passages at the opposite sides of the burner element through which the gas to be heated flows in divided streams from said inlet portion to said outlet portion, said burner having a combustible mixture chamber and burner orifices opening from said chamber toward the outlet portion of said passage.
6. A heater for gaseous material, comprising
10 refractory material surrounding and forming the wall of a streamlined flow passage including an outlet portion of expanding nozzle form and an inlet portion in line with said outlet portion, a burner element in said passage between the inlet
15 and outlet portions thereof and comprising an outer portion of refractory material in position to be engaged by fluid flowing through said passage, and formed with a fuel space and with burner orifices opening to said passage adjacent the inlet end of said outlet portion.

7. A heater for gaseous material, comprising a flow passage including a burner chamber extending transversely to the length of said passage, and inlet and outlet portions opening to said burner chamber at opposite sides of the latter, an elongated burner located in and extending longitudinally of said chamber and spaced from the wall of said chamber to provide passages at the opposite sides of the burner element through which the gas to be heated flows in divided streams from 10 said inlet portion to said outlet portion, said burner having an inlet for gaseous fuel and having burner orifices opening to said passage and separate means for passing gaseous material to be heated into said flow passage and for passing 15 a combustible mixture into said fuel space.

8. A heater as specified in claim 7, in which the said flow passage is surrounded by a heat insulating wall of refractory material.

FREDERIC O. HESS. 20
